TABLE OR THE LIKE

David Chapman, Chicago, Ill., and Richard G. Reineman, Muskegon, Mich., assignors to The Brunswick-Balke-Collender Company, Chicago, Ill., a corporation of Delaware

Application February 13, 1953, Serial No. 23,618

Term of patent 14 years

(Cl. D33—14)

To all whom it may concern:

Be it known that we, David Chapman and Richard G. Reineman, citizens of the United States, residing at Chicago, in the county of Cook, State of Illinois, and Muskegon, in the county of Muskegon, State of Michigan, have invented a new, original, and ornamental Design for a Table or the like, of which the following is a specification, reference being had to the accompanying drawings, forming a part thereof.

In the drawings:

Fig. 1 is a perspective view of a table or the like, looking diagonally at the front thereof, showing our new design;

Fig. 2 is a perspective view looking diagonally at the right hand corner of Fig. 1;

Fig. 3 is a front elevational view thereof;

Fig. 4 is a side elevational view looking at the right hand end of Fig. 3.

The dominant features of our design are shown in full lines.

We claim:

The ornamental design for a table or the like, as shown and described.

DAVID CHAPMAN.

RICHARD G. REINEMAN.
